DESIGN FOR A TOY ANIMAL FIGURE OR THE LIKE

Walter Lantz, Universal City, Calif.

Application May 31, 1945, Serial No. 119,827

Term of patent 14 years

(CL. D34—2)

To all whom it may concern:

Be it known that I, Walter Lantz, a citizen of the United States, residing at Universal City, in the county of Los Angeles and State of California, have invented a new, original, and ornamental Design for a Toy Animal Figure or the like, of which the following is a specification, reference being had to the accompanying drawing, forming a part thereof.

I claim:

The ornamental design for a toy animal figure or the like, as shown.

WALTER LANTZ.
